DESIGN FOR A DRESS

Mordecai N. Mayehoff, New York, N. Y.

Application May 19, 1939, Serial No. 85,079

Term of patent 3½ years

To all whom it may concern:

Be it known that I, Mordecai N. Mayehoff, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front perspective view of a dress showing my new design.

Fig. 2 is a rear view on a reduced scale of the dress shown in Figure 1.

The characteristic feature of my design resides in the combination on the specific dress disclosed of the specific pockets arranged on the belt and skirt as shown.

I claim:

The ornamental design for a dress, substantially as shown and described.

MORDECAI N. MAYEHOFF.
